UNITED STATES PATENT OFFICE

CLYDE J. BRYANT, OF CHICAGO, ILLINOIS, ASSIGNOR OF ONE-HALF TO JOHN P. WALLIS,
OF CHICAGO, ILLINOIS.

MAIL-OPENING MACHINE.

1,047,493.

Specification of Letters Patent. Patented Dec. 17, 1912.

Application filed April 17, 1911. Serial No. 621,699.

To all whom it may concern:

Be it known that I, CLYDE J. BRYANT, a citizen of the United States, residing at Chicago, in the county of Cook and State of Illinois, have invented a new and useful Improvement in Mail-Opening Machines, of which the following is a specification.

My invention relates particularly to machines adapted for cutting or opening envelopes; and my primary object is to provide a machine which will operate to rapidly and effectively open mail matter.

It may be stated preliminarily that in the preferred form of the invention a rotary cutter and motor therefor are mounted in a box or cabinet the top of which is equipped with a guide or guides through which the envelopes may be fed on edge to be operated on by the cutter. The blades of the cutter are preferably so arranged as to not only produce a shearing action on the envelopes, but also to create a suction into the cabinet at the cutting point, so that the fine particles of paper, as they are sheared off, will be drawn into the cabinet, rather than thrown as dust into the room.

The invention is illustrated in its preferred embodiment in the accompanying drawings, in which—

Figure 1 represents a vertical sectional view of an envelop-cutter constructed in accordance with my invention, the section being taken as indicated at line 1 of Fig. 2; Fig. 2, a plan view of the machine; Fig. 3, a broken transverse section taken as indicated at line 3 of Fig. 2; Fig. 4, a perspective view of a plural guide employed; Fig. 5, a broken transverse vertical section taken as indicated at line 5 of Fig. 1, and showing the manner in which the hanger which supports the motor and cutter-wheel is pivoted; Fig. 6, a broken vertical section taken as indicated at line 6 of Fig. 1 and showing the adjustability of said hanger; Fig. 7, a broken plan view of the cutter-wheel; Fig. 8, a broken edge elevational view of the cutter-wheel; Fig. 9, a perspective view of one of the blades of the cutter-wheel; Fig. 10, a broken plan view showing a modification in which a mechanical feed for the mail matter is provided; Fig. 11, a broken sectional view taken as indicated at line 11 of Fig. 10; Fig. 12, a transverse section taken

as indicated at line 12 of Fig. 11; and Fig. 13, a broken lower side view of the cabinet top and guide-equipped plate employed.

In the form of my invention illustrated in Figs. 1 to 9 inclusive, it comprises a body or casing A having a top A' provided with a letter-guide A²; and a motor B located in the casing A and having a slightly inclined (from the vertical) shaft on which is mounted a cutter-wheel B' having blades adapted to enter a slot with which the guide A² is provided in its base portion. The casing A may be of any suitable form and construction. Preferably it comprises a box-form body 1 provided in its base with a withdrawable drawer 2, and having a lid connected by hinges 3 and secured by a catch or lock 4. The top A' of the casing thus constitutes the upper member of the hinged lid, and the closure may be opened to give access to the cabinet and to lift the cutting device and motor out of the cabinet. The motor B is preferably suspended from the top of the casing, and the top of the casing is preferably provided throughout its length with a longitudinal channel through which the letters may be fed. Thus, I preferably provide the top member A', which may be of wood, with a slot 5 which extends throughout the length of said member and which accommodates a metal guide plate 6 having a longitudinal recess 7 which extends the whole length of the plate and may be of any desired width, two or three inches in width ordinarily being ample. The metal member 6 is equipped near one end with depending lugs 8 which support the pivots 9 of a U-form hanger 10, as will be clearly understood from Figs. 1 and 5. The other arm of the hanger 10 is equipped at its upper end with a stud 11 which is received in a slot 12 of a supporting lug 13 which depends from the plate 6. The member 13 is equipped with a set-screw 14 which extends from beneath into the slot, or opening, 12 and supports the stud 11. Thus the hanger may be adjusted to vary the relation of the cutter-wheel to the guide-member A², according to the depth of cut which it is desired that the wheel shall effect. The motor B is preferably an electric motor supported on the web of the U-form hanger 10 in such manner that the shaft 15 of the motor makes

a very slight angle with the vertical. The cutter-wheel B' is mounted on the upper end of the shaft 15, so as to turn directly with the shaft. Peripherally, the cutter-wheel 5 has blades 16 which are obliquely disposed, both with reference to the radii of the cutter-wheel and with reference to radial planes which pass perpendicularly through the cutter-wheel. Thus, as will be understood 10 from Figs. 2 and 7, each blade 16 makes an angle with any corresponding radius of the wheel. That is to say, the outer ends of the blades are set in advance of the inner ends of the blades, so that a shearing action will 15 result in the operation of the machine. In addition to this, the blades are non-perpendicularly set with reference to the body of the wheel. That is to say, each blade inclines somewhat from a perpendicular to 20 the wheel-body, the cutting edge of the blade being in advance of the base or supporting edge of the blade. Each blade is preferably of the form shown in Fig. 9, having a base-portion 17 which is received by a slot of 25 compound obliquity with which the cutter-wheel is provided at its periphery; and having a cutting portion 18 which projects laterally from the upper side of the peripheral portion of the wheel, as will be readily 30 understood from Fig. 1. The outer, upper corner of each blade presents an advance point, which begins the shearing action.

The bottom of the depressed portion of the plate 6, which forms the channel 7, is 35 recessed or cut away centrally, as indicated at 19. The plural guide A² comprises the comparatively thin plate 20 equipped on its upper surface with a series of parallel flanges, or guide members, 21, between which 40 are afforded the guide spaces through which the letters may be passed, while on edge. The plate 20 and the base portions of the flanges 21 are recessed centrally, as indicated at 22, thus affording notches adapted 45 to receive the cutting portions 18 of the blades 16. It will be understood that the upper walls and end walls of the notches 22 co-act with the upper and end shearing edges of the portions 18 of the blades of the 50 cutter-wheel. Thus, as envelopes are fed through the guides of the guide member A², the cutter-wheel, revolving at a rapid speed, will operate to shear off successive minute portions of the lower edges of the envelopes 55 as the envelopes are passed through the guides. Of course, the movement of the envelopes through the guides is continuous, and as the small bits of paper are sheared off, they are drawn into the cabinet by the 60 suction action of the fan-like cutter blades.

The member 6, which is transversely slotted at 19 to accommodate the upper portion of the slightly inclined cutter-wheel, is also recessed as indicated at 23 to accommodate 65 the end portions of the plate 20 of the

guide-member A², so that the upper surface of the plate 20 will be flush with the bottom of the longitudinal recess or groove 7 of the plate 6. The member A² is secured in position in any suitable manner, as by means of 70 screws 24.

When desired, the lid of the cabinet may be opened or inverted to give access to the motor and to enable the adjustment of the bracket or hanger 10 to be effected. The 75 cabinet is provided with a screened outlet 25 which enables the air which is drawn into the cabinet by the revolving cutter-wheel to escape from the cabinet.

In the modification shown in Figs. 10 to 80 13 inclusive, I have illustrated a mechanical feed, whereby the letters may be fed singly, but very rapidly, through the guide and subjected to the cutting action of the rotary cutter. It is my purpose to make the hand-feed and the mechanical feed interchangeable. An important advantage may thus be gained, since, for instance, a party requiring a machine of comparatively small capacity may thus be enabled to purchase the 85 cheaper hand-feed machine, and later, when increased business requires it, may obtain the interchangeable parts and add the mechanical feed to the machine. In the modification, a plate 6^a is substituted for the 90 plate 6 of the previously described construction; the plate 6^a being interchangeable with the plate 6. The plate 6^a is provided with a longitudinal groove or channel 7^a, which is 95 relatively narrow and is formed in the depressed longitudinal central portion of the plate 6^a. A pair of shafts 26 and 26^a extend through the plate 6^a on one side of the guide-groove 7^a and have their lower ends belted 100 or otherwise geared to the shaft 15 of the 105 motor B. The shafts 26 and 26^a are equipped at their upper ends with rollers, or pulleys, 26^b and 26^c, which co-act with rollers 27^b and 27^c mounted on shafts 28 carried by a slide 29 mounted in transverse 110 guides 30. Springs 31 are attached to the sliding plate 29 and the plate 6^a, and tend to hold the rollers 27^b and 27^c in contact with the companion rollers 26^b and 26^c. The 115 pair of rollers 26^b and 26^c are connected by a belt 32; and the pair of rollers 27^b and 27^c are connected by a belt 33. The belts 32 and 33 are thus disposed parallel with each other and with their operative portions in contact, or substantially so. It will be 120 understood that letters may be fed through the groove 7^a, with their upper portions gripped by the belts 32 and 33. In other words, the belts will feed the letters, while the lower portions of the letters will depend 125 into the groove 7^a, the lower edges resting upon the bottom of the guide-groove. The cutter-wheel B', which is employed in lieu of the cutter-wheel B', is of somewhat smaller diameter; but by separating the 130

dates the end portions of the plate 20 of the

rollers 26^b and 27^b further from the rollers 26^a and 27^a, the same size cutter-wheel may be employed. The guide 7^a is transversely cut by a slot 34 which accommodates the blades of the cutter-wheel.

5 When desired, the plate 6 may be removed from the machine illustrated in Figs. 1 to 9 inclusive, and the plate 6^a and equipment may be substituted therefor, the same 10 motor being employed. Envelops supplied to the belts will be automatically fed through the guide-groove 7^a, and the edge portions presented to the cutter will be cut away. Suitable provision may be made for 15 introducing the envelops rapidly between the feed belts. Thus, if desired one of the feed-belts may be lengthened sufficiently to enable a package of envelops to be pressed thereagainst, so that the envelops will be 20 carried singly, in rapid succession, between the belts. A very rapid feed may thus be obtained in the operation of the machine, so that the machine will have a very large capacity.

25 The machine is simple of construction; easy of operation; may be constructed at moderate cost; and is thoroughly effective for its purpose. In operation, the small particles of paper and paper-dust are drawn 30 into the cabinet and settle in the box or drawer 2, which is removable, to enable its contents to be emptied from time to time. If desired, the belts 32 and 33 may be removed, and the rollers may directly engage 35 the envelops and perform the feeding function. This is possible where the cutter-wheel is of comparatively small diameter, so that the rollers are not necessarily widely separated in a direction lengthwise 40 of the envelop guide.

45 My invention renders it possible to expedite immeasurably the opening of mail in large establishments; and, even in small establishments having a comparatively small amount of mail, the invention may be used very advantageously, since the machine, in its simplest form, can be supplied at a very moderate cost.

The foregoing detailed description has 50 been given for clearness of understanding only, and no undue limitation should be understood therefrom, but the appended claims should be construed as broadly as permissible in view of the prior art. I may add 55 that so far as I am aware, no invention has heretofore been produced which would serve the purpose of my invention.

What I regard as new and desire to secure by Letters Patent is -

60 1. In a machine of the character set forth, the combination of a cabinet equipped externally with a guide through which envelops may be passed edgewise, said guide having a slot in its base portion, and a 65 rotary cutter-wheel having fan-like shear-

ing-blades adapted to effect shearing action and draw the air through said slot into the cabinet.

2. In a machine of the character set forth, the combination of an envelop-guide having its base portion provided with a transverse slot, a wheel provided peripherally with laterally-projecting obliquely-set, forwardly-inclined shearing-blades adapted to co-act with said slot, and means for rotating 70 said wheel.

3. In a machine of the character set forth, the combination of an envelop-guide, a cutter mounted on an inclined shaft and having lateral upwardly-projecting blades, means 80 for rotating said shaft, and means for varying the inclination of said shaft.

4. In a machine of the character set forth, the combination of a cabinet provided with a top and equipped with a guide through 85 which envelops may be moved on edge, a hanger depending from said top, a motor mounted on said hanger, and a cutter-wheel carried by the motor shaft.

5. In a machine of the character set forth, 90 the combination of a cabinet equipped with a lid which may be opened, an envelop-guide mounted on said lid and having in its base portion a transverse slot, and a revolving cutter supported through the 95 medium of said lid and disposed in the cabinet beneath the lid.

6. In a machine of the character set forth, the combination of a cabinet having a top provided with a separable guide-equipped 100 plate, and cutting means within said cabinet and carried by said plate.

7. In a machine of the character set forth, the combination of a cabinet having a top equipped with a separable plate and provided with a channel extending through the 105 plate, a hanger depending from said plate, a motor mounted on said hanger, and a cutter above said motor and actuated thereby.

8. In a machine of the character set forth, 110 the combination of a member provided with a longitudinal channel, and an envelop-guide in said channel provided with a plurality of parallel passages, and a rotary cutter beneath said member operative to remove 115 the edge portions of the envelops fed through said guide.

9. In a machine of the character set forth, the combination of a guide-plate provided on its upper surface with a channel, a guide-member provided with plural passages, a motor suspended beneath said plate, and a cutter beneath said plate and actuated by 120 said motor.

10. In a machine of the character set forth, 125 the combination of a guide-plate provided on its upper surface with a channel, a guide-member provided with a plurality of parallel flanges and having its base portion provided with a transverse slot, and a rotary 130

cutter beneath said plate having its operative portion working through said slot.

11. In an envelop cutting machine, the combination of a cabinet provided with a movable top closure which is adapted to be opened, said closure equipped with a guide through which envelopes can be moved on edge, said guide provided at its base portion with a transverse shearing-slot, and a rotary cutter and motor therefor suspended from said closure, said rotary cutter equipped with shearing blades adapted to move through said shearing-slot.

12. In a machine of the character set forth, 15 the combination of envelop-guiding means having a plurality of longitudinal channels with transversely notched walls at their base portions, affording shearing-shoulders, and a rotary cutter having shearing-blades 20 working through said notches and co-acting with said shoulders to shear successive bits from the edge-portions of envelopes moving through said channels.

13. In a machine of the character set forth, 25 the combination of a cutter having shearing-blades provided with oblique shearing-edges having advance points adapted to effect first cutting of the envelopes, an envelop guide constructed to permit envelopes to be fed 30 therethrough on edge and provided in its

base portion with a slot through which said blades operate, and a shearing-shoulder associated with said slot and co-acting with said shearing-blades.

14. In a machine of the character set forth, 35 the combination of an envelop guide constructed to permit envelopes to be fed therethrough on edge, a shearing-shoulder associated with the base-portion thereof, and a cutter having shearing-blades co-acting with 40 said shoulder and provided with oblique shearing edges having advance points which are first to enter the envelopes in the shearing action.

15. In a machine of the character set forth, 45 the combination of an envelop guide constructed to permit envelopes to be fed therethrough on edge, a shearing shoulder associated with the base-portion thereof, and a rotary cutter-wheel having shearing-blades 50 co-acting with said shoulder, said shearing blades having oblique shearing edges presenting advance points and having also inclined oblique front surfaces, whereby said blades are adapted to effect shearing action 55 and draw the air and severed bits inwardly.

CLYDE J. BRYANT.
